UNITED STATES PATENT OFFICE

WILLIAM J. PURSER, OF MINERAL RIDGE, OHIO, ASSIGNOR TO THE BOSTWICK STEEL LATH COMPANY, OF NILES, OHIO, A CORPORATION OF OHIO

REENFORCED METAL LATH

Application filed February 24, 1930. Serial No. 430,985.

This invention relates to improvements in reenforced metal lath of the non-expanded type, and has for its general object to provide a metal lath structure of the so-called "truss loop" type embodying a novel combination and relative arrangement of features designed to impart longitudinal and transverse stiffness to the lath and at the same time to provide effective keying formations to retain the plaster upon the lath.

More particularly, the object of the invention is to incorporate the desirable features of the so-called "truss-loop" type of metal lath in a metal lath sheet of corrugated, ribbed or channeled form, whereby the sheet stiffening and reenforcing effectiveness of the truss loops are enhanced by reason of the corrugated nature of the sheet which results in a novel arrangement of the truss loops relative to one another, and whereby the stiffening effectiveness of the alternate ribs and channels of the corrugated sheet is enhanced by the truss loops which are formed in said ribs and channels.

With the foregoing and other objects in view, the invention consists in the novel construction, combination and arrangement of features as will be hereinafter more fully described, illustrated in the accompanying drawings and defined in the appended claims.

In the drawings, wherein like characters of reference denote corresponding parts in the different views:—

Figure 1 is an outer face view of a section of metal lath fabricated in accordance with the present invention.

Figure 2 is an inner face view of a section of the lath.

Figure 3 is a perspective view of a section of the lath.

Figure 4 is a longitudinal section on the line 4—4 of Figure 1.

Figure 5 is a transverse section on the line 5—5 of Fig. 1; and

Figure 6 is a view similar to Fig. 5 illustrating an alternative embodiment of the invention.

Referring to the drawings in detail, it will be observed that the present lath consists essentially of a body or base A of sheet metal

suitably bent to provide a plurality of parallel ribs 10 and a depression 11 between each adjacent pair of said ribs, said ribs and said depressions being continuous longitudinally of the body or base A and preferably being of considerably greater width than depth. Thus, basically, the present lath consists of a corrugated metal sheet composed of alternate relatively wide ribs and relatively wide depressions therebetween extending continuously longitudinally of the sheet with the bottoms of the depressions lying in a common plane and the tops of the ribs lying in another common plane parallel to and spaced outwardly with respect to the plane of the bottoms of the depressions.

Along the top of each rib 10 adjacent to each side thereof is formed an outwardly directed rib stiffening bead 13, while connecting these beads at longitudinally spaced intervals are transverse ribs or beads 14. Thus, the top of each rib 10 is divided by the transverse ribs or beads 14 into a plurality of plaster seats 15 each of which, in accordance with the invention, is longitudinally slotted adjacent to the beads 13, 13, respectively, as indicated at 16, and has the metal between said slits pressed together and arched outwardly to provide a so-called truss loop 17 the characteristics of which are well known in the art.

In a similar manner, the bottom of each depression 11 is formed at longitudinally spaced intervals with outwardly directed transverse ribs or beads 18, and between each adjacent pair of these ribs or beads the metal of the body or base A is longitudinally slit adjacent to the side walls of the depressions and, between said slits, is pressed together to provide an outwardly directed arched truss loop 19.

Preferably, the ribs or beads 14 of the ribs 10 are disposed in alignment transversely of the body or base A and midway between the ribs or beads 18, which latter also are disposed preferably in alignment transversely of the body or base A, so that the truss loops of the depressions 11 are staggered with respect to the truss loops of the ribs 10. Thus, the inherent rigidity and strength of the

structure afforded by the ribs 10 with their truss loops 17 disposed in a plane spaced outwardly with respect to the plane of the bottoms of the depressions 11 and their truss loops 19 is increased and the final result is a metal lath fabrication possessed of maximum strength and stiffness both longitudinally and transversely so that any danger of same buckling or partaking of a wave motion when 10 plaster is being applied thereto is substantially eliminated.

Instead of the truss loops 17 being formed to extend outwardly from the plaster seats 15, said truss loops obviously may be directed 15 inwardly from said plaster seats as indicated at 17^a in Fig. 6 of the drawings, in which event the outermost portions of said truss loops may lie within, or substantially within, the plane of the bottoms of the depressions 11 20 with the result that the lath structure, considered as an entirety, and in all other respects a duplicate of the lath structure shown in Figs. 1 to 5, will be of materially less over all thickness than the lath structure of said 25 Figs. 1 to 5.

Without further description it is thought that the features and advantages of the invention will be readily apparent to those skilled in the art, and it will of course be understood that changes in the form, proportion 30 and minor details of construction may be resorted to, without departing from the spirit of the invention and scope of the appended claims.

35 I claim:

1. In a reenforced metal lath, in combination a sheet of metal corrugated to provide parallel ribs and a depression between each adjacent pair of ribs, said ribs having pairs of laterally spaced longitudinally extending slits and the metal between each pair of said slits being crushed together and arched to provide truss loops.

2. In a reenforced metal lath, in combination a sheet of metal corrugated to provide parallel ribs and a depression between each adjacent pair of ribs, the bottoms of said depressions having pairs of laterally spaced longitudinally extending slits and the metal 50 between each pair of said slits being crushed together and arched to provide truss loops.

3. A reenforced metal lath consisting of a sheet of metal corrugated to provide parallel ribs and a depression between each adjacent pair of ribs, beads formed along the tops of said ribs near the sides thereof, said ribs between said beads having pairs of laterally spaced longitudinally extending slits and the metal between each pair of said slits being crushed together and arched to provide truss loops.

4. A reenforced metal lath consisting of a sheet of metal corrugated to provide parallel ribs and a depression between each adjacent 65 pair of ribs, beads formed along the tops of

said ribs near the sides thereof, transverse beads formed across the tops of said ribs at spaced intervals, and a truss loop between said side beads and each adjacent pair of said transverse beads.

5. A reenforced metal lath consisting of a sheet of metal corrugated to provide parallel ribs and a depression between each adjacent pair of ribs, transverse ribs formed across the bottoms of said depressions at spaced intervals, and a truss loop formed with the bottom of each depression between each adjacent pair of said transverse ribs.

6. A metal lath consisting of a sheet of metal corrugated to provide parallel ribs and a depression between each adjacent pair of said ribs, transverse beads at spaced intervals across the top of said ribs and across the bottoms of said depressions, respectively, and outwardly directed truss loops formed with the tops of said ribs and the bottoms of said depressions, respectively, between adjacent pairs of said transverse beads.

7. A metal lath structure comprising a sheet of metal corrugated to provide parallel ribs and a depression between each adjacent pair of ribs, and stiffening formations extending transversely across said ribs at points spaced longitudinally along said ribs.

8. A metal lath structure comprising a sheet of metal corrugated to provide parallel ribs and a depression between each adjacent pair of ribs, and stiffening formations extending transversely across said depressions at points spaced longitudinally along 100 said depressions.

9. A metal lath structure comprising a sheet of metal corrugated to provide parallel ribs and a depression between each adjacent pair of ribs, and stiffening formations extending transversely across said ribs and said depressions at points spaced longitudinally along said ribs and said depressions respectively.

10. A metal lath structure comprising a sheet of metal corrugated to provide parallel ribs and a depression between each adjacent pair of ribs, a stiffening formation along the top of each rib at each side thereof and other stiffening formations extending transversely across said ribs at points spaced longitudinally along said ribs.

11. A metal lath structure comprising a sheet of metal corrugated to provide parallel ribs and a depression between each adjacent pair of ribs, a stiffening formation along the top of each rib at each side thereof and other stiffening formations extending transversely across said ribs and across the bottoms of said depressions at points spaced longitudinally along said ribs and said depressions, respectively.

12. A metal lath structure comprising a sheet of metal corrugated to provide parallel ribs and a depression between each adjacent 130

pair of ribs, a stiffening formation along the top of each rib at each side thereof and other stiffening formations extending transversely across said ribs and across the bottoms of said depressions at points spaced longitudinally along said ribs and said depressions, respectively, the transverse stiffening formations of said ribs being staggered with respect to the transverse stiffening formations of said depressions.

13. A metal lath structure comprising a sheet of metal corrugated to provide parallel ribs and a depression between each adjacent pair of ribs, a stiffening formation along the top of each rib at each side thereof, stiffening formations extending transversely across said ribs at points spaced longitudinally along the ribs, and truss loop formations integral with each rib between said first mentioned stiffening formations and between each adjacent pair of said transverse stiffening formations.

14. A metal lath structure comprising a sheet of metal corrugated to provide parallel ribs and a depression between each adjacent pair of ribs, stiffening formations extending transversely across said ribs at points spaced longitudinally along said ribs, and truss loop formations on said ribs between each adjacent pair of said transverse stiffening formations.

15. A metal lath structure comprising a sheet of metal corrugated to provide parallel ribs and a depression between each adjacent pair of ribs, stiffening formations extending transversely across said ribs and said depressions at points spaced longitudinally along said ribs and said depressions respectively, and truss loop formations integral with said ribs and with the bottoms of said depressions between each adjacent related pairs of said transverse stiffening formations, respectively.

16. A metal lath structure comprising a sheet of metal corrugated to provide parallel ribs and a depression between each adjacent pair of ribs, a stiffening formation along the top of each rib at each side thereof, other stiffening formations extending transversely across said ribs and across the bottoms of said depressions at points spaced longitudinally along said ribs and said depressions, truss loop formations integral with said ribs between said longitudinal reenforcing formations and between each adjacent pair of the transverse reenforcing formations of said ribs, and other truss loop formations integral with the bottoms of said depressions between each adjacent pair of the transverse reenforcing formations of said depressions.

In testimony whereof I hereunto affix my signature.

WILLIAM J. PURSER.
